UNITED STATES PATENT OFFICE

163,065

CHILD'S PUSH VEHICLE

La Von I. Powell, Denver, Colo.

Application December 4, 1950, Serial No. 13,261

Term of patent 14 years

(Cl. D34—15)

To all whom it may concern:

Be it known that I, La Von I. Powell, a citizen of the United States of America, residing at Denver, in the county of Denver and State of Colorado, have invented a new, original, and ornamental Design for Child's Push Vehicle, of which the following is a specification, reference being had to the accompanying drawing, forming part thereof.

In the drawing:

Fig. 1 is a side view of a child's push vehicle showing the new design;

Fig. 2 is a top view thereof; and

Fig. 3 is a front view thereof.

I claim:

The ornamental design for a child's push vehicle, as shown.

LA VON I. POWELL.
